BUILDING CONSTRUCTION

James Palmer Boggs, Denver, Colo.

Application December 24, 1935, Serial No. 56,035

6 Claims. (Cl. 20—1)

This invention relates to the construction of buildings, such as may be employed for the housing of humans and animals and for the storage and protection of materials and supplies, and more particularly to building construction of prefabricated type, and has as an object to provide an improved construction of the character and for the purpose set forth.

A further object of the invention is to provide an improved construction and arrangement of units cooperable to form a complete building of prefabricated type.

A further object of the invention is to provide an improved prefabricated building construction which is arranged for ready assembly without the employment of specialized skill and facilities.

A further object of the invention is to provide an improved building construction susceptible of ready disassembly for transportation to and reerection on a new site.

A further object of the invention is to provide an improved prefabricated building construction which is readily susceptible of expansion and contraction to provide a building of a size adapted to varying specific requirements.

A further object of the invention is to provide an improved prefabricated building construction wherein the constituent units are relatively small, sufficiently light to permit of convenient handling, and easily transportable.

A further object of the invention is to provide an improved prefabricated building construction wherein the constituent units may be readily prefabricated of relatively inexpensive, commonly available materials with skill and facilities commonly available.

A further object of the invention is to provide an improved prefabricated building construction particularly adaptable for erection on sites not conveniently accessible, which is rigid and substantial in erected form, which provides a maximum of available, unobstructed, interior space, and which is particularly desirable for the temporary housing of rapidly accumulated concentrations of men, animals and supplies.

My invention consists in the construction, arrangement and combination of elements herein-after set forth, pointed out in my claims, and illustrated by the accompanying drawings, in which—

Figure 1 is a half-sectional top plan view of an erected building wherein are embodied the principles of the instant invention. Figure 2 is a side elevation of the construction shown in Figure 1.

Figure 3 is a half-sectional end elevation, on an enlarged scale, of the construction shown in Figures 1 and 2. Figure 4 is a section, on a further enlarged scale, taken transversely of the showing of Figures 1 and 2, a portion of the view being broken away to conserve space. Figure 5 is a fragmentary, detail section, on a further enlarged scale, transversely of the ridge construction and arrangement employed in the instant invention. Figure 6 is a cross sectional view taken on the indicated line 6—6 of Figure 5. Figure 7 is a fragmentary, detail section transversely through a panel joint and purlin arrangement employed in the instant invention. Figure 8 is a fragmentary, detail section taken transversely of an outer, lower wall corner construction employed in the present invention. Figure 9 is a fragmentary, detail cross section taken on the indicated line 9—9 of Figure 8. Figure 10 is a fragmentary, detail cross section taken on the indicated line 10—10 of Figure 8. Figure 11 is a fragmentary, detail cross section similar to Figure 10 and illustrating an outer corner joint construction employed in the present invention. Figure 12 is a top plan view of a floor panel construction employed in the present invention. Figure 13 is a side elevation of the panel construction illustrated in Figure 12. Figure 14 is a top plan view of a wall panel construction employed in the present invention. Figure 15 is a cross section taken on the indicated line 15—15 of Figure 14. Figure 16 is a top plan view of a window wall panel employed in the present invention. Figure 17 is a cross section taken on the indicated line 17—17 of Figure 16.

In the construction of the improvement as shown, the erected building is illustrated as comprising a plurality of rigidly-assembled, identical, bents suitably spaced apart for covering and interconnection by means of a plurality of unitary panels to form the desired enclosure. Each of the bent assemblies comprises a pair of arch segments 20 arranged for suitable interconnection of adjacent ends to form a substantially semi-circular arch member, and a pair of identical tie-beam units 21 interconnectable at their adjacent ends to form a tie-beam assembly adapted to engage the arch assembly adjacent its spring line to immobilize the otherwise free ends of the arch assembly. Each of the arch sections 20 is formed as a rigid, arcuate unit comprising a segment of substantially ninety degrees of curvature and may be of any suitable or desired specific construction, the drawings illustrating laminated arch segments 20 constructed of a plurality of

relatively thin, easily curved elements rigidly interconnected in overlying relation to form the desired unit, which construction is readily adapted to development from any ordinary lumber with the usually-available facilities. To form the arch assembly of a given bent, corresponding ends of two arch segments 20 are abutted in slightly spaced relation and are rigidly interconnected by means of tie-plates 22 and 23 overlapped across the abutted ends of the arch segments and removably clamped in such relation by means of a plurality of bolts 24 engaging through said plates and ends of the arch segments. To facilitate such limited articulation as may be desired for various reasons between the interconnected ends of the arch segments 20, a short cylindrical block or pipe section 25 is preferably interposed and clamped between the abutted ends of each pair of arch segments 20. Each pair of arch segments 20 is thus suitably rigidly interconnected to form a substantially semi-circular arched unit with the abutted, interconnected ends of the arch segments at the crown of the arch unit. The tie-beam units 21 each comprise a pair of identical beam elements 26 arranged in parallel relation and spaced apart a distance approximating the width of an arch segment 20 by means of spacer blocks 27 positioned and rigidly clamped between the members 26 by means of bolts 28. The blocks 27 are positioned at each end of a tie-beam unit 21 and the blocks 27 with corresponding inner ends of said tie-beam units are arranged to be employed in the removable aligned interconnection of a pair of said tie-beams to form one rigid, continuous beam assembly, as is indicated in Figure 4, other blocks 27 being clamped between the members 26 in spaced relation inwardly of the beam assembly from the blocks 27 at the free ends of said assembly to provide a socket adjacent each end of the beam assembly of a size to receive a free end of the arch assembly, which latter is thereby supported and held against movement of its otherwise free ends. The ends of the arch assembly may be firmly clamped between the members 26 and blocks 27 by tightening of the bolts 28 to thus form a rigid, arched bent unit adapted to be positioned with the tie-beam assembly on and in contact with the ground surface or other suitable foundation and with the arch assembly rising in a vertical plane from its tie-beam support.

When employed in the erection of a building a plurality of the bents formed as above described are arranged in uniformly spaced, parallel relation with corresponding crowns and ends aligned perpendicularly to the disposition of their tie-beams, and are interconnected in such relation by means of a relatively long, straight ridge beam 29 extending longitudinally in interconnecting relation between the crown points of adjacent bents and notched at each bent to engage against and fit snugly over each arch assembly. The ridge beam 29 may be a single unit for buildings of relatively limited length, or may be a composite unit formed through the rigid interconnection of shorter elements, when such construction is expedient or desirable. Additional beams 30, similar to the ridge beam 29, are disposed longitudinally of the frame provided by the spaced parallel bents in parallel relation with said ridge beam 29 and spaced uniformly therefrom to divide each arch assembly into uniform segments on each side of said ridge beam, said beams 30 thus being employed as purlins notched over each arch assembly to suitably space, brace

and position the frame formed thereby. The beams 29 and 30 preferably are not fixed or secured to the arch assemblies in any manner other than by their notched engagement thereover, but are positioned and held relative to such arch assemblies through cooperation with enclosure panels hereinafter described.

The frame provided by the arch assemblies and beams 29 and 30 presents a plurality of rectangular open spaces of preferably uniform size, which spaces are adapted to be closed by means of suitable fitted panels to form an enclosure. The panel elements employed, to cover the frame above described may be of any desired specific construction, naturally varying widely in details of construction according to the materials employed therein, but a simple and preferred form of such construction is illustrated in Figures 14-17. As shown in the figures just noted, the panels are generally of two types, plain and windowed, which panels are interchangeable on the building frame and may be arranged and assorted thereon to meet the requirements of a given installation. The plain panel illustrated in Figures 14 and 15 is indicated generally by the numeral 31 and comprises a rectangular frame suitably braced and covered smoothly with matched sheathing or equivalent material to present a smooth, unbroken exterior surface, the sheathing extending somewhat beyond the panel frame along the normally lower long margin of the panel to provide a step or shoulder, as is clearly shown in Figure 7. The inner surface of the panel 31 may be finished, when desired, with a sheet of finish or insulating material, such as is indicated by the numeral 32, such finish providing a dead-air insulating space between inner and outer surfaces of the panel as well as enhancing the appearance and finish presented by said panel interiorly of the completed building. The windowed panel shown in Figures 16 and 17 and indicated by the numeral 33, is essentially the same as the panel 31 and differs from the latter only in that the bracing of the panel frame is arranged to outline a window aperture whereon is suitably supported a window sash unit 34. For purposes of ventilation, the window sash unit 34 is preferably hinged along its normal upper margin to the panel 33 and thereby arranged to swing outwardly and upwardly from said panel at times, and suitable guard strips 35 and sills 36 are provided and arranged to prevent leakage through the joints between the sash unit 34 and panel assembly 33. As in the case of the panel 31, the interior surface of the panel 33 may be covered, save for the window aperture by a sheet of finish or insulating material 37, the window aperture being screened, when desired, to protect the interior of the building against the entrance of flies and other insects.

A floor for the building is provided in the form of a plurality of identical panels illustrated in Figures 12 and 13 and indicated generally by the numeral 38, each of said panels comprising a plurality of identical joist members 39 each having a length approximating the distance between the longitudinal center lines of adjacent tie-beam assemblies, which members 39 are arranged in parallel spaced relation and are rigidly secured to suitable flooring material 40 to form panel units having a length equal to one half the width of the building and a width equal to the spacing between the center lines of adjacent tie-beam units, said panels being notched as indicated at 41 for engagement about arch seg-

ments rising from the tie-beam units. As is clearly shown in Figure 1, two floor panel units 38 may be positioned and aligned to form the space between adjacent bents of the building 5 frame, said panels extending beyond the arch segments to vertical alignment of their outer ends with the ends of the tie-beam assemblies, as is clearly shown in Figure 8, a suitable strip or shoulder 42 being provided on each arch segment 10 at the line of floor panel intersection therewith to engage under and support the notched portions of the floor panels engaged thereabout. With the floor panels 38 in position to entirely 15 cover the floor space of a given frame arrangement, a row of panels 31 is positioned with their lower long margins engaging ends of the floor panels between adjacent arch assemblies and their upper margins resting against the lower 20 of the purlins 30, the projecting portion of the panel sheathing extending downwardly past the junction of the side panel frame with the surface of the floor panel for weather protection of the joint therebetween, as is clearly shown in Figure 8, adjacent edges of the panel units 31 25 being abutted to form vertical joints aligned with and over the longitudinal median lines of the arch assemblies. The panels 31 are held in the desired relation with and on the building frame assembly by means of suitable bolts 43 30 preferably engaging through a suitable metallic retainer bar 44 positioned in aligned recesses formed in adjacent margins of the panels 31 in overlying relation with the joint therebetween and extending through said panels in embracing 35 relation with and on opposite sides of the adjacent arch segment 20 to clamping connection through a retainer bar 45 engaging against the inner side of said arch segment, the bolts 43 thus serving to firmly clamp the lower adjacent 40 corners of adjacent panels 31 to an arch segment 20 and simultaneously hold the upper margins of said panels firmly against the lower of the purlins 30. With the lower row of panels 31 45 positioned as above described, a second row of panels, shown in this instance as comprising windowed panels 33, is installed in covering relation with the frame spaces between the first and second of the purlins 30, said panels engaging with their lower long margins supported 50 on the upper long margins of the first row of panels and their upper long margins resting against the second of the purlins 30, lower adjacent corners of the second row of panels being clamped to the adjacent arch segment 20 by 55 means of bolts 43 and plates 44 and 45 in the manner previously described for the first row of panels, as is clearly shown in Figure 7. Additional rows of panels 31 or 33, in such arrangement as may be desired, are installed in covering 60 relation with the building frame spaces and are clamped in their installed position by means of bolts and retainer plates in the manner previously described, until the frame assembly is entirely covered to form the enclosure desired, the panel units meeting on the ridge beam 65 29 being clamped to said beam by means of an angled ridge plate 46 overlying said panels and clamped by means of bolts 47 to a suitable plate 48 engaged beneath and extending at each end laterally beyond the crown portion of the arch 70 assembly. End portions of the frame assembly are closed by means of a central, vertical, framed panel assembly 49 operatively supporting a hinged door 50 and an adjustable ventilating 75 louvre 51, of any desired specific construction,

and by means of complementary panel units 52 framed and shaped to fill the spaces between the central end panel 49 and the marginal outline formed by the panels 31 and 33, portions of the end panels 31 and 33 projecting slightly beyond 5 and fitting closely against the adjacent margins of the panels 52 and 49, as is clearly shown in Figure 11. End portions of the end panels 31 and 33 of the assembly are clamped to one end of an angle bar 53 engaged about the arch segment 20 of the end frame bent, the other end of the angle bar 53 being clamped by means of a suitable bolt to an end panel 52 or 49, which latter is thereby held in the desired relation with the frame assembly and panels 31 and 33, thereby 10 completing a windowed housing enclosure to which access may be had through the doors 50 positioned in either end thereof. 15

While the improvement is illustrated as constructed largely of lumber, which material is generally available in stock sizes adapted to the construction shown and described, it is to be understood that the units of the improved construction may be fabricated of metal, suitable composition of matter, such as synthetic lumber, 20 plaster compositions, and the like, all of which lend themselves to suitable adaptation to the specific shapes and arrangements employed for the units of the improved construction, all such materials being contemplated as equivalents for 25 the lumber employed as illustrated and being readily usable in giving practical effect to the improvement without in any way departing from the novel principles described and hereinafter 30 claimed. 35

Since many changes, modifications and variations in the specific construction, form and arrangement of the elements shown and described may be had without departing from the spirit of the invention, I wish to be understood as being 40 limited solely by the scope of the appended claims, rather than by any details of the illustrative showing and foregoing description.

I claim as my invention—

1. In a building construction having an arched, skeleton frame and interchangeable panel elements bridging in covering relation between the arched elements of said frame, means for positioning and removably securing said panel elements relative to said frame, said means comprising uniformly-spaced, parallel purlins longitudinally of said frame and engageable by upper margins of said panel elements, shoulders on lower margins of said panel elements adapted to engage over upper margins of adjacent panel elements, and means engaging through lower corners of said panel elements for clamping engagement with elements of said frame assembly. 45 50 55

2. A building construction comprising a plurality of uniformly-spaced, parallel frame units, 60 each of said units comprising a rigid, coplanar assembly of two identical unbraced, arcuate rib segments interconnected at adjacent ends to form an arch and a tie-beam base element removably interconnecting the other ends of the rib segments at the spring line of said arch, means 65 removably interconnecting said units to form a skeleton frame, and panel means removably bridging between said units to enclose and floor said skeleton frame. 70

3. In a building construction having a panel-enclosable, skeleton frame, a transverse unitary frame assembly comprising a pair of arcuate, unbraced, rib segments interconnected at adjacent ends to form an arch and a tie-beam ele- 75

ment removably engaging between the other ends of said segments at the spring line of said arch.

4. In a building construction having a panel-enclosable, skeleton frame, a transverse unitary frame assembly comprising a pair of identical, unbraced, arcuate ribs of uniform cross-section throughout their lengths and separably interconnected at abutted ends to form an arch, and a unitary tie-beam assembly separably inter-
10 connecting the other ends of said ribs at the spring line of said arch.

5. In a building construction having a panel-enclosable, skeleton frame, a transverse unitary frame assembly comprising a pair of identical, unbraced, arcuate ribs of uniform cross-section separably interconnected at abutted ends to form an arch, a tie-beam unit assembly formed with sockets adjacent its ends adapted to receive the free ends of said ribs, and means for clamping
15 20 the ends of said ribs within said sockets to sepa-

rably connect said tie-beam assembly as a chord-base in interconnecting relation between the spaced ends of said ribs and at the spring line of said arch.

6. In a building construction having an arched skeleton frame and panel elements bridging in covering relation between the arched elements of said frame and overlapping at their lower margins on upper margins of the next lower adjacent panel element, means detachably connecting said panel elements with said frame, said means comprising bolts extending inwardly through corresponding adjacent lower corners of separate panel elements and positioned on opposite sides of and extending beyond a frame member, and a clamp bar slidably on and bridging between inner ends of bolts paired on opposite sides of a frame member for clamped engagement against the inner side of said member.

JAMES PALMER BOGGS. 20
